UNITED STATES PATENT OFFICE.

PAUL YUNGLING, OF LOS ANGELES, CALIFORNIA, ASSIGNOR TO OIL FIELDS SPECIAL-TIES COMPANY, OF LOS ANGELES, CALIFORNIA, A CORPORATION OF CALIFORNIA.

BRAKE-DRUM CONSTRUCTION.

Application filed June 9, 1925. Serial No. 35,909.

This invention relates to a brake of the external contracting band type engageable with a brake drum. Such brakes become worn from use, and when applied with much force 5 for a long period of time become in many instances excessively hot. The present invention has for its primary object the provision of a brake of the type referred to so constructed as to efficiently conduct and radiate from the brake surfaces the heat generated therein.

In the drilling of oil wells by the rotary method, it is common practice to employ a winch structure for elevating and lowering 15 tools in the hole. Such structures are commonly termed draw works. A drum for winding and unwinding the tool supporting cable is employed. In lowering tools into the hole, the drum is turned by reason of the 20 weight of the string of tools and cable, and the speed of unwinding is controlled by brakes secured to the drum. Commonly, there is a brake drum on each end of the winding drum and brake bands therefor. 25 Due to the weight of the tools and the great depth of such holes with consequent length of cable, the brake drums become excessively hot, the heat being conveyed to the winding drum and the whole glowing and often flying 30 to pieces, resulting in injury to the workers and other damage. The embodiment of the invention disclosed herein is intended to be applied to a draw works. A more specific object of this invention is to 35 provide a drum having a wear and heat insulating lining and to provide in the band a good heat conducting path to the outer surface thereof.

These objects together with other objects 40 and corresponding accomplishments are obtained by means of the embodiment of my invention illustrated in the accompanying drawing, in which:

Fig. 1 shows a fragment of a structure for 45 supporting a draw works and an end view of the drum therefor, particularly showing the brake drum and brake band; Fig. 2 is a fragmentary enlarged end elevation with a wear block holding ring partly broken away

to show the brake drum construction; and 50 Fig. 3 is a section as seen on the line 3—3 of Fig. 2.

Referring more particularly to the drawing, 5 indicates the drive shaft upon which the drum is mounted, it being arranged so 55 that the drum may be driven thereby or may idly rotate. This portion of the structure forms no part of my invention and will not be further described. The winding drum is indicated generally by 6 and secured thereto 60 by any suitable means is the brake drum comprising the ring 7 for attachment to the drum and the cylindrical brake drum surface 8. Extending transversely of the drum are undercut teeth or tenons 9. The tenons 65 are spaced so as to form dovetail grooves for receiving liner blocks 10. These blocks are slipped into position laterally and held against lateral displacement upon the drum by means of end rings 11 and bolts 12. The 70 blocks 10 should be made of some heat insulating and wear resisting material, such as asbestos. Hard compounds of asbestos and slate held together by a suitable binder to form a composite block are well known and 75 will serve the purpose. Certain hard woods may also be used. The outer surface of these blocks frictionally engage the brake band 14 which is flexible and anchored at one end as indicated by 15. The other end of the band 80 is secured to tightening linkage indicated generally by 16. The band disclosed herein is provided with flanges 17 which overhang the blocks. The drum is open so that air 85 may reach the under surface thereof.

In operation, the band is contracted upon the drum against the wear and heat insulating blocks. The heat generated by the frictional resistance of the band against the blocks, due to the character of the blocks, 90 will not travel freely inwardly. However, the band being made of metal such as steel presents a conducting surface and the heat will pass outwardly therethrough to the ambient atmosphere. In the ordinary type of brake of this character the heat travels inwardly heating the drum. Further, it has sometimes been the practice to line the brake

band with wear resisting material which prevents or hinders the heat from passing outwardly.

drum and a brake band of heat conducting material wrapped around said drum and engaged with said lining. 10

What I claim is:

- 5 A brake structure comprising a drum of relatively high heat conductivity, a lining of heat insulating material comprising blocks detachably mounted on the exterior of said

In witness that I claim the foregoing I have hereunto subscribed my name this 25th day of May, 1925.

PAUL YUNGLING.
